UNITED STATES PATENT OFFICE.

CHARLES P. BREESE, OF NORFOLK, VIRGINIA.

METHOD OF MANUFACTURING PACKING-RINGS.

1,368,887.

Specification of Letters Patent. Patented Feb. 15, 1921

Application filed March 16, 1917. Serial No. 155,309.

To all whom it may concern:

Be it known that I, CHARLES P. BREESE, a citizen of the United States, residing at Norfolk, in the county of Norfolk and State 5 of Virginia, have invented a certain new and useful Method of Manufacturing Packing-Rings, of which the following is a specification.

This invention relates to a method of 10 manufacturing packing rings particularly adaptable for engines, pumps and the like.

The ordinary form of packing ring is objectionable because when the ring expands, a point diametrically opposite the slit in 15 the ring acts as a fulcrum, causing unequal radial expansion so that the ring frequently breaks on account of crystallization or other causes.

10 The ideal packing ring structurally is in 20 the form of a spiral, because it may have both radial and axial expansion to not only efficiently pack, but also eliminate liability of "ring-slap", as well as other disadvantages.

25 It is the purpose of my invention to provide a packing ring of spiral form with the pitch of the spiral equal to the width of the cut, so that the ring will have both axial and radial resiliency and substantial uni- 30 form expansion throughout.

In carrying out my invention, I construct the ring from a cylinder by cutting a spiral slot or groove in said cylinder, the pitch of which is equal to the width of the slot or 35 groove. For example, if the width of the slot or groove is one-quarter inch, the pitch of the cutter will be such as to give four cuts to the inch. If the width of the cut is three-eighths inch, the cutter will be set to 40 make eight cuts to three inches and so on. I also prefer to arrange the cutters so that they will be in the plane of the cut and of the thickness of the cut. By maintaining the pitch of the cut equal to the width thereof, 45 the inner edge of the beginning of the cut will be in substantially the same plane as the outer edge of the finish of the cut, so that when a plurality of rings are formed from a single cylinder, each ring may be sepa- 50 rately broken away from its adjacent member in a convenient manner. After the rings are formed as just described, the ends of the convolutes are severed by cuts that determine the angles of the ends of the spi- 55 rals, and of the offsetting web, and at the same time determine the spaces between said

ends and web permitting circumferential contraction of the ring. The spiral portions of the ring will be of uniform cross sectional area throughout and the offsetting 60 web may be of any desirable width. The rings are then collected, placed in a jig, clamped together and ground to size in the usual manner.

In order to assist in a proper comprehension of the means by which the method may be carried out, I have illustrated diagrammatically the relation between the cutters and the cylinder in forming the rings, it being understood that the drawing does not 70 necessarily resemble a machine such as will actually be used, but merely illustrates the method.

In the drawings:

Figure 1 represents a view in elevation of 75 a machine for carrying out my process;

Fig. 2 is an elevational view of a cylinder cut to form five rings.

Fig. 3 is a diagrammatic view showing the angular position of the work with relation to the cutters;

Fig. 4 is a diagrammatic view of the kerfing or finishing cutters, and

Fig. 5 is a detail perspective view of the finished ring.

Referring now to Fig. 1, 10 designates a bed plate on which is a turret 11 which carries a vertically adjustable frame 12 on which is a chuck 13 longitudinally and rotatably driven by the lead screw 14 and drive 15. The chuck may carry a cylinder 16 which has been previously cast and interiorly rough cut to provide a wall of substantially uniform thickness, so that when the spiral is formed and the ring finished, it will be of uniform cross sectional area. 17 designates a shaft in fixed arbors 18 and 19, said shaft being driven by a pulley 20 and a belt 21. It will be observed that the rotary cutters are arranged in alternating relation, those designated 22 of larger diameter alternating with those of smaller diameter designated by numeral 23, there being one more than two cutters for each ring, the extra cutter 22^a serving to cut 105 off the end of the stock at the end of the ring. I have shown means for making the rings in multiples, the diagrammatic mechanism illustrated indicating means for making five rings at one time from a single cylinder. It is obvious, however, that multiples of this arrangement may be provided,

or a single ring may be cut from a relatively short cylinder if desired.

When the cylinder 16 is placed in its chuck, it is first adjusted vertically by turning the crank 24 on the shaft 25 threaded in the sliding wedge blocks 26 and 27, which, by moving on the inclined faces 28 and 29 move the cylinder 16 into engagement with the cutters 22 and 23. The cutters are rotated at a relatively greater speed than the speed of the cylinder, for, the rotation of the cylinder 16 is equal to the speed of the cut, because the pitch of the lead screw bears a definite relation to the width of the cut. In order to provide smooth edges on the rings, I prefer to maintain the cutters in the plane of the cut, as shown in Fig. 1, and preferably of substantially the same width as the cut, and by turning the turret to provide the proper angularity between the work and the cutters, the cut cylinder will have the form shown in Fig. 2 with the outer edge of the first ring in the plane of the inner edge of the second ring, so that the cut of the rings will substantially sever them or so closely approximate the severing of the rings as to permit them to be easily broken apart. Each individual ring is then subjected to oblique cutters 30 and 31 which cut away excess material from the offset web 32 connecting the convolutes 33 and 34 of the spiral ring 35, whereby the free ends of the convolutes 33 and 34 are inclined in the planes of the edges of the web and whereby the width of the web is established. A ring constructed by this process will have, when confined, equal expansive force throughout its entire circumference. The rings thus formed may then be collected and placed in a sizing jig preparatory to having a number of the rings clamped together in the usual manner so that they will be frictionally held against independent rotation. The collected rings are then subjected to the usual grinding preparatory to finishing them.

It will be apparent that rings produced as above described will be cut rings, instead of wound or produced by bending, and each will have uniformly spaced spirally related convolutes of uniform sectional area throughout, with a connecting web, and with the metal of the web and convolutes retaining the same molecular status and occupying the same relative positions, when the ring is left unrestricted, as the metal of these parts had in the original blank from which the

ring is cut. Such a ring will have resiliency to give both radial and axial expansion so that not only will the radial expansion of the ring cause it to, at all times, bear against the surrounding surface to provide uniform wearing, but the axial expansion of the ring will maintain a close fit in the piston groove and prevent "ring-slap."

I claim:

1. The herein described method of manufacturing piston rings which consists in providing a cylinder and then cutting a spiral ring therefrom, the pitch of the spiral being equal to the width of the cut.

2. The herein described method of making packing rings which consists in providing a cylinder, then cutting a spiral ring therefrom, the pitch of the spiral being equal to the width of the cut, and in maintaining the cutter in the plane of the cut.

3. The herein described method of making packing rings which consists in providing a cylinder, then cutting a spiral ring therefrom, the pitch of the spiral being equal to the width of the cut, whereby the two halves of the spirals will be connected by a web and then removing the corners of the web to provide an offset web of suitable width.

4. The herein described method of making packing rings which consists in providing a cylinder, then cutting a spiral ring therefrom, the pitch of the spiral being equal to the width of the cut, whereby the two halves of the spirals will be connected by a web and then removing the corners of the web to provide an offset web of suitable width, and at the same time cutting the free ends of the spiral on a plane parallel with the edges of the web.

5. The herein described method of making packing rings which consists in providing a cylinder, the wall of which is substantially of equal thickness throughout, then subjecting said cylinder simultaneously to a plurality of spiral cuts, the pitch of the spiral being equal to the width of the cut so that the outer edge of one spiral will be in substantially the plane of the inner edge of the next succeeding spiral, then separating said rings, then removing surplus material to make the rings of uniform width throughout and then finishing said rings.

The foregoing specification signed at Washington, D. C., this 3d day of March, 1917.

CHARLES P. BREESE.
